Primary Examiner — Janice Hallmark*Assistant Examiner* — Adedoyin Taiwo Odeyale(74) *Attorney, Agent, or Firm* — Schroeder & Siegfried, P.A.(57) **CLAIM**

The ornamental design of a septic chamber as shown and described.

DESCRIPTION

FIG. 1 is a front perspective view of a septic chamber showing my new design;

FIG. 2 is a rear perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof; and,

FIG. 8 is a front elevational view thereof.

Broken lines illustrate portions of the septic chamber that form no part of the claimed design. Additional broken lines show a symbolic break in length where the appearance of any portion of the septic chamber between these break lines forms no part of the claimed design.
